UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

CLEANSING DEVICE FOR ROCK DRILLS

Application filed June 24, 1930. Serial No. 463,429.

This invention relates to rock drills, but more particularly to a cleansing fluid conveying means for rock drills.

The primary object of the present invention is to assure the thorough cleansing of drill holes of great depth.

Another object of the invention is to simplify and render more durable devices of this character.

Still another object of the invention is to permit ready inspection of the means whereby cleansing fluid is conveyed to the drilled hole.

Other objects will be in part obvious and in part pointed out hereinafter.

In the accompanying drawings illustrating the invention and in which similar reference characters refer to similar parts,

Figure 1 is a side elevation of a drilling mechanism supported by a wagon mounting and having the invention applied thereto,

Figure 2 is an enlarged longitudinal sectional view of a portion of a rock drill equipped with a cleansing fluid conveying means constructed in accordance with the practice of the invention, and

Figure 3 is a transverse view taken on the line 3-3 of Figure 2 looking in the direction indicated by the arrows.

Referring to the drawings A designates the frame of a wagon which is supported on axles B and C, each axle carrying a pair of wheels D so that the wagon may be hauled along a roadway or about the floor of a quarry. A vertical frame E secured at its lower end to the wagon frame A provides guideways for the saddle F of the rock drill G to direct the rock drill along the intended line of cut in the rock H. The frame E may be braced by one or more struts J.

The rock drill G operates upon a drill steel K which may be of the Leyner type and accordingly is shown provided with lateral lugs L. The drill steel K extends into the front head O of the rock drill and the lugs L are engaged by a chuck P in the front head O and which may be rotated by suitable rotation mechanism (not shown) whereby rotation of the chuck will cause rotation of the drill steel.

Ordinarily in drilling down holes the weight of the drilling apparatus is sufficient to maintain the bit Q of the drill steel K firmly against the rock. Means are provided for quickly elevating the drilling apparatus upon the completion of a cut and such means may include a power hoist R mounted on the frame A and operatively connected to the saddle F by a cable S. The cable is shown trained over a guide sheave T rotatably mounted at the upper end of the frame E.

In deep hole drilling operations drill steels of unusually large diameter are employed and since the drill hole is therefore of considerable diameter the force of a blast of cleansing fluid applied in the usual manner is soon dissipated. Hence, difficulty is experienced in removing the cuttings from the drill hole as it becomes deeper.

In accordance with the present invention the cleansing fluid is conveyed to the bottom of the drill hole by a tubular member or pipe U which encircles the drill steel and extends from a point near the front head to a point preferably near the bit Q. The pipe U has a branch V communicating therewith which serves as the inlet pipe for conveying cleansing fluid to the pipe U. Accordingly the pipe V is shown connected as by means of a clamp W to a conduit X, which in turn may be connected to any suitable source of cleansing fluid. It has been found practical to connect the conduit X to the exhaust port of the rock drill but I do not intend to limit the invention to this construction nor to the use of any particular source of cleansing fluid.

Cleansing fluid conveyed by the conduit X passes through the branch V into the pipe U and from thence it passes to the bottom of the drill hole to dislodge the cuttings from around the bit Q. The cuttings are forced upwardly through the space between the pipe U and the wall of the drill hole to the surface. The space within the interior of the pipe U forming the channel for incoming cleansing fluid and the space about the periphery of the pipe U forming the channel for outgoing cleansing fluid and cuttings.

may be varied by selecting pipes U of different sizes but are preferably somewhat restrictive so that the cleansing fluid flowing therethrough will be maintained at a suitably high velocity to remove all cuttings from the drill hole.

In order to prevent the escape of cleansing fluid at the upper end of the pipe U a tube Y is fitted with its ends over the upper end 10 of the pipe U and over the forward extremity of the front head O. This tube may consist of rubber or like impervious material possessing the additional property of flexibility. In the preferred construction the tube Y is secured to the upper end of the pipe 15 U and to the forward extremity of the front head O by clamps Z and b respectively. The adjacent ends of the pipe U and front head O are shown flared outwardly to prevent the clamps Z and b from sliding thereover.

20 The clamp b may comprise a pair of half sections c and d adapted to be drawn together about the front head O by bolts e extending through both members c and d. The clamp Z may be similar in all essential respects to clamp b and also consist of a pair of members which are adapted to be drawn together about the pipe U to rigidly secure the tube Y thereto.

25 The clamp Z is preferably connected to the clamp b by flexible means, as for instance, cables f of sufficient strength to transmit the full weight of the pipe U and the associated cleansing fluid conveying means to the front head O. The ends of the cables f are shown 30 inserted into laterally extending ears g and h on the clamps Z and b respectively, and are secured therein by any suitable means. It is intended that the tube Y shall be relieved of the weight of the pipe U and that 35 the same shall be carried solely by the cables f.

In assembling the device the cables f may 40 first be secured in the ears g and h thus joining each half section of the clamp b to the clamp Z. One end of the tube Y is then 45 forced over the end of the pipe U and clamped thereto by the clamp Z. With the rock drill in its lowered position the tube Y may 50 be flexed and the free end thereof passed over the forward extremity of the front head and 55 clamped thereto by the clamp b. The conduit W may then be connected to branch V thus completing the assembly of the cleansing 60 fluid conveying means. It is intended that the cleansing fluid conveying apparatus remain connected to the rock drill during movement of the truck since in the elevated position of the rock drill the pipe U is clear of the ground.

With the rock drill in its lowered position and the pipe V brought to a substantially horizontal position which is made possible by the flexibility of cables f and tube Y, the 65 drill steel K may be readily inserted into the

70 pipe U. Then upon elevating the rock drill, the pipe U and drill steel K may be carried into alignment with the rock drill and the drill steel inserted into the front head O and engaged by the chuck preparatory to the drilling operation.

Upon completion of the drilling operation the drilling apparatus is elevated until the bit Q of the drill steel K is above the level of the ground. The drill steel K may then be 75 freed from the chuck and lowered until its upper end is clear of the front head O. Lowering the rock drill while simultaneously swinging the pipe U laterally will permit the 80 drill steel to be readily removed from the pipe.

I claim:

1. In a rock drill, the combination of a front head and a drill steel extending into the front head, a tubular member encircling the drill steel and adapted to convey cleansing fluid into the drill hole to remove cuttings therefrom, a flexible tubular member encircling the adjacent ends of the front head and the first said tubular member and forming a fluid tight connection between the first said tubular member and the front head, spaced means for securing the flexible tubular member to the adjacent ends of the front head and the first said tubular member, and flexible means connecting said spaced means for transmitting the weight of the first said tubular member to the front head.

2. In a rock drill, the combination of a front head and a drill steel extending into the front head, a tubular member encircling the drill steel and adapted to convey cleansing fluid into the drill hole to remove cuttings therefrom, a flexible tubular member encircling the adjacent ends of the front head and the first said tubular member, clamps for securing the flexible tubular member to the front head and the first said tubular member, and flexible cables connecting the clamps whereby the weight of the first said tubular member is supported by the front head.

3. In a rock drill, the combination of a front head and a drill steel extending into the front head, a tubular member encircling the drill steel and extending to a point adjacent the cutting bit thereof, a flexible tubular member having its ends encircling the adjacent ends of the front head and the first said tubular member and forming a fluid tight connection between the first said tubular member and the front head, spaced clamps encircling the ends of the flexible tubular member for securing said flexible tubular member to the said adjacent ends of the front head and the first tubular member, a fluid connection opening through the wall of the first said tubular member for conveying cleansing fluid to the first said tubular member whereby such cleansing fluid will be directed into the drill hole, and flexible cables

having their ends secured to the clamps and extending between the front head and the first said tubular member for supporting the first said tubular member and the connection.

- 5 4. In a rock drill, the combination of a front head and a drill steel extending into the front head, a tubular member encircling the drill steel, a flexible member encircling the adjacent ends of the front head and the
10 tubular member, spaced means for securing the flexible member to the said adjacent ends of the front head and the tubular member, and flexible members connecting said means.

15 In testimony whereof I have signed this specification.

CHARLES C. HANSEN.
